UNITED STATES PATENT OFFICE

164,213

BIRD DRINKING FOUNTAIN

David L. White, Miami, Fla.; Ruth L. White administratrix of said David L. White, deceased

Application May 6, 1949, Serial No. 2,497

Term of patent 3½ years

(Cl. D12—2)

To all whom it may concern:

Be it known, that I, David L. White, a citizen of the United States of America, residing at Miami, in the county of Dade, and State of Florida, have invented a new, original, and ornamental Design for Bird Drinking Fountain, of which the following is a specification; reference being had to the accompanying drawing, forming part thereof.

In the drawing:

I claim:

The ornamental design for a bird drinking fountain, as shown.

DAVID L. WHITE.
